US00D667594S

(12) **United States Design Patent**
Valle et al.

(10) **Patent No.:** **US D667,594 S**
(45) **Date of Patent:** **** Sep. 18, 2012**

(54) **PET HABITAT**

(75) Inventors: **Andrea M. Valle**, Dover, NJ (US); **Ryan Rutherford**, Belleville, NJ (US); **Jonathan Willinger**, Tenafly, NJ (US)

(73) Assignee: **J.W. Pet Company, Inc.**, Teterboro, NJ (US)

(**) Term: **14 Years**

(21) Appl. No.: **29/399,060**

(22) Filed: **Aug. 9, 2011**

Related U.S. Application Data

(60) Division of application No. 29/388,392, filed on Mar. 29, 2011, now Pat. No. Des. 646,028, which is a division of application No. 29/344,316, filed on Sep. 28, 2009, now Pat. No. Des. 637,367, and a division of application No. 29/335,011, filed on Apr. 7, 2009, now Pat. No. Des. 607,618, said application No. 29/344,316 is a division of application No. 29/335,011, which is a continuation-in-part of application No. 29/306,978, filed on Apr. 21, 2008, now Pat. No. Des. 592,362, which is a division of application No. 29/266,259, filed on Sep. 15, 2006, now Pat. No. Des. 586,957, said application No. 29/335,011 is a continuation-in-part of application No. 29/325,159, filed on Sep. 26, 2008, now Pat. No. Des. 631,619.
